THERMOSTATIC SWITCH

Franklin M. Gates, West Hartford, and Herbert W. Courtney, Farmington, Conn., assignors to The Smith Gates Corporation, Plainville, Conn., a corporation of Connecticut

Application November 7, 1947, Serial No. 784,722

11 Claims. (Cl. 200—139)

1

The invention relates to a switch adapted to be automatically opened or closed in accordance with changes in the temperature. A switch embodying the invention is particularly adapted for use in conjunction with a heating unit, which is started when the temperature falls below a predetermined critical temperature so as to close the switch and which is stopped when the temperature rises above the said critical temperature so as to open the switch. While not necessarily so limited, a switch embodying the invention is particularly adapted for use in or as a part of an immersion water heater.

The general object of the invention is to provide a switch of the type described which is compact, simple and inexpensive, and which is dependable and is sensitive to very small temperature changes.

A specific object of the invention is to provide simple thermostatically controlled toggle means for moving the movable contact of the switch to its "on" and "off" positions with a snap action.

Another specific object of the invention is to provide a simple and effective stop for positively limiting the extent of movement of the bimetallic element forming a part of the switch.

A still further specific object of the invention is to provide an advantageous relationship between the bimetallic element and the other parts of the switch. The mounting and relationship of the bimetallic element is particularly useful when the switch is incorporated in an immersion water heater.

A still further object of the invention is to provide a simple and effective means for adjusting the bimetallic element to change the before-mentioned critical temperature.

Other objects of the invention will be apparent from the drawing and from the following specification and claims.

In the drawing we have shown in detail a preferred embodiment of the invention, but it will be understood that various changes may be made from the construction shown, and that the drawings are not to be construed as defining or limiting the scope of the invention, the claims forming a part of this specification being relied upon for that purpose.

Of the drawing,

Fig. 1 is a plan view of a switch embodying the invention, the movable contact being shown in its "on" position.

Fig. 2 is a view similar to Fig. 1, but with the movable contact shown in its "off" position.

2

Fig. 3 is a vertical sectional view taken along the line 3—3 of Fig. 1.

Fig. 4 is a side view.

Fig. 5 is a detail view of the flexible strip which carries the movable contact.

Fig. 6 is a fragmentary vertical sectional view taken along the line 6—6 of Fig. 1.

A switch embodying the invention is particularly adapted to be of relatively small size. It is shown in the drawing on a comparatively large scale for the sake of clarity.

Referring to the drawing, 10 represents an insulating base on which all of the other parts of the switch are mounted. As shown, the base 15 is a circular disc with a depending annular flange. For convenience of description it will be assumed that the switch is positioned with the base horizontal, but the invention is not so limited and the switch may be variously positioned.

20 Secured to the base near one side thereof is a support 12, comprising a metallic bar which is perpendicular to the base and which has an angle portion secured to the base by means of a rivet 14 extending therethrough. Rigidly or fixedly 25 secured to the support 12, as for instance by means of a rivet 16, is a thin resilient metallic strip 18. The strip 18 is perpendicular to the base and it extends from the said support 12 parallelly with the base and preferably approximately across the center thereof. Secured to the strip 18 near the end thereof opposite the said support 12 is an electrical contact 20 which is preferably in the form of a round button having a convex contact face.

30 Secured to the base near the opposite side thereof is a support 22, comprising a metallic bar which is perpendicular to the base and which has an angle portion secured to the base by means of a rivet 24 extending therethrough. Carried 35 by the support 22 is a stationary electrical contact 26 positioned to be engaged by the movable electrical contact 20.

Connected with the rivets 14 and 24 which hold the supports 12 and 22 are wire terminals 28 and 40 30 which may be of any usual or preferred form. It will be seen that when the movable contact 20 is engaged with the stationary contact 26, as shown in Fig. 1, an electrical circuit is established through the switch between the said wire terminals.

45 The resilient strip 18 has a longitudinally extending opening therein which is entirely surrounded by integral portions of the strip. As shown, the longitudinally extending opening includes parallel longitudinal slots 34 and 36 and

also includes a transverse portion 38 extending between the said longitudinal slots. A longitudinal bow spring 32 is provided which is connected with the strip 18 at that end of the opening therein which is adjacent the movable contact. The bow spring 32 may be formed integrally with the metal of the strip 18 and it is so shown. When formed integrally, the bow spring is initially in the same plane as the main body of the strip.

A toggle member 40 is provided which is supported entirely by the strip 18. Preferably the toggle member 40 is formed of insulating material, and is a flat plate parallel with the front of the base 10. One end of the toggle member is notched and is pivotally engaged at 42 with the metal of the strip 18 at the end of the opening therein remote from the contacts, and the other end of the toggle member is notched and is pivotally engaged at 44 with the adjacent end of the bow spring 32. The length of the toggle member between the pivotal connections 42 and 44 is such that the spring 32 is bowed as shown in Figs. 1 and 2 when the toggle member is in place. The axes of pivotal movement at 42 and 44 are perpendicular to the base 10, and the axis at 42 is in the plane of the strip 18. By reason of the pivotal connections at 42 and 44, a toggle action is provided by the toggle member 40 and by the bow spring 32. When the toggle member is in the position shown in Fig. 1, the bow spring holds the movable contact 20 in engagement with the stationary contact 26. When the toggle member is in the position shown in Fig. 2, the bow spring holds the movable contact 20 out of engagement with the stationary contact 26.

In order that the toggle member 40 may be more effectively supported by the strip 18 and by the bow spring 32, projections 43, 43 are provided at the ends of the pivotal edge 42 on the strip 18 and projections 45, 45 are provided at the ends of the pivotal edge 44 on the spring 32. These projections are at opposite sides of the toggle member 40 as shown in Fig. 3 and they assist in supporting it and in holding it in place.

The portion of the toggle member 40 effective for toggle action is that between the axes 42 and 44. In order that the toggle member 40 may be operated it has a relatively large extension 41 at one side as clearly shown in Figs. 1 and 2.

For pivotally moving the toggle member 40 about its pivotal axis at 42 in accordance with changes in temperature, there is provided a bimetallic element 46. The position and shape of the bimetallic element 46 may be widely varied, but I preferably provide a bimetallic element comprising a strip which is circularly curved to substantially conform to a hypothetical geometric cylinder perpendicular to the base. Preferably and as shown, the hypothetical geometric cylinder to which the strip 46 substantially conforms is concentric with the circular base 10, but has a somewhat smaller diameter. The flexible strip 18, the contacts 20 and 26, the bow spring 32 and the toggle member 40 are all within the said geometric cylinder.

The bimetallic strip 46 is so constituted that it tends to deflect outward to increase the radius of curvature when the temperature increases, and that it tends to deflect inward to decrease the radius of curvature when the temperature decreases. For supporting the bimetallic strip 46 on the base there is provided an arm 48 having a portion 50 which extends away from the

base and perpendicularly thereto. The bimetallic element 46 is secured to the said portion 50 by suitable means, as for instance by a rivet 52. The bimetallic strip 46 is provided near its opposite end with a hole through which extends a pin 54 which is carried by the toggle member 40 and which is parallel with the base 10.

It may be assumed that when the parts are in the positions shown in Fig. 1, the ambient temperature is slightly below a predetermined critical temperature. With the parts in the said positions, the axis of connection at 44 between the bow spring 32 and the toggle member 40 is at the side of the strip 18 which is opposite the stationary contact 26. The result is that the bow spring 32 flexes the strip 18 in the direction to hold the movable contact 20 in engagement with the stationary contact 26. If the switch is in the control circuit of a heating unit, the said unit is operated to increase the ambient temperature. As the temperature increases to a point slightly above the said critical temperature, the radius of curvature of the bimetallic element 46 is increased and the toggle member 40 is swung in the counterclockwise direction about the axis at 42. As soon as this movement of the toggle member 40 carries the axis at 44 to the other side of the resilient strip 18, the bow spring 32 acts to flex the strip 18 in the opposite direction so as to separate the movable contact 20 from the stationary contact 26, as shown in Fig. 2. Preferably, a pin 56 is carried by the base adjacent the movable end of the resilient strip 18. This pin is in position to engage the back of the contact button 20 to limit movement of the contact in the "off" direction.

With the switch in the "off" position shown in Fig. 2 the heating unit is not operated and there is a tendency for the temperature to decrease. As the temperature decreases to a point slightly below the critical temperature, the toggle member 40 is swung in the clockwise direction to restore the axis at 44 to a position at or near that shown in Fig. 1, whereupon the bow spring 32 acts to again flex the resilient strip 18 and to return the movable contact 20 to its position of engagement with the stationary contact 26 as shown in Fig. 1.

The toggle member 40 moves very slowly in each direction in accordance with the movement of the bimetallic strip in response to changes in temperature. However, as the axis at 44 moves from one side of the strip 18 to the other, the movable contact is moved quickly with a snap action either to its "off" position as shown in Fig. 2, or to its "on" position as shown in Fig. 1.

A suitable means is preferably provided for limiting the extent of deflection of the bimetallic element 46, such limitation being preferably effected by limiting the extent of angular movement of the toggle member 40. As shown the said member 40 is provided with a hole 58 which is perpendicular to the base. Secured to the base within the aforesaid geometric cylinder is a pin 60 which extends into the hole 58, the said pin having a diameter somewhat smaller than that of the hole. The relationship between the diameter of the pin 60 and the diameter of the hole 58 is such that there is no engagement during normal operation of the switch, that is, when the bimetallic strip is deflected only within normal predetermined limits. This will be apparent from an inspection of Figs. 1 and 2. However, when the switch is not in use it may be subjected to temperatures much greater or much less than

the critical temperature, the result being that the bimetallic element may tend to deflect outward or inward to extents far greater than the extents necessary for operating the toggle member. Any excessive deflection of the bimetallic element and any excessive movement of the toggle member are prevented by the engagement of the stationary pin 60 with the side of the hole 58. The pin 60 positively prevents movement of the toggle member 40 and of the bimetallic strip 46 beyond certain wider predetermined limits which are outside of the aforesaid predetermined limits of normal movement.

The bimetallic element 46 is preferably bodily adjustable so as to change the critical temperature. The said bimetallic element may be variously moved, but preferably it is adjusted circularly about an axis at or approximately at its center of curvature. The before-mentioned arm 48 is connected with the base 10 by means of a rivet 62, the said arm being pivotally movable about the said rivet. The axis of the rivet is at the center of the base and is therefore at or approximately at the center of curvature of the bimetallic element. For adjusting the arm 48 about the axis of the rivet 62 there is provided a member 64 which extends through an aperture in the base and which can be turned therein. The member 64 has an eccentric head 66 which is entered in a longitudinal slot 68 in the arm 48. The head 66 has a screwdriver slot therein, and by means of a screwdriver inserted in the said slot the said member 64 may be turned to angularly adjust the arm 48 and the bimetallic element 46 in either direction. The member 64 frictionally engages the base so that it will remain in any position to which it may be moved. When the arm and the bimetallic element are moved in the clockwise direction, the critical temperature is increased and when they are moved in the counterclockwise direction the critical temperature is decreased.

As already stated, a switch embodying the invention is particularly adapted for use in, or as a part of, an immersion water heater. When so used the switch is enclosed within the same casing as the heating unit of the heater. The drawing shows a portion of an enclosing casing 70. The said casing is indicated by dot-and-dash lines and the showing thereof is intended to be merely diagrammatic. The casing does not of itself constitute any part of the present invention.

When the switch is enclosed in a casing such as 70 the bimetallic element 46 is, throughout its entire length, closely adjacent the inner wall of the casing. The casing 70 is immersed in the water to be heated, and thus the bimetallic element is in position to respond readily and quickly to changes in temperature transmitted through the casing.

When the switch is used otherwise than in an immersion water heater it may be provided with a separate cover, not shown, for preventing mechanical damage and for excluding dust.

What we claim is:

1. In a thermostatic snap switch, the combination of a resilient metallic strip having a longitudinally extending opening therein entirely surrounded by integral portions of the strip, the said strip being fixedly supported at one end, a movable contact carried by the strip near the opposite end thereof, a stationary contact positioned to be engaged and disengaged by the movable contact, a longitudinal bow spring connected with

the strip at that end of the opening therein which is adjacent the movable contact, a toggle member entered in the opening in the strip and entirely supported by the said strip, the said toggle member being pivotally engaged at one end thereof with the metal of the strip at the end of the opening remote from the contacts and being pivotally engaged at its opposite end with the adjacent end of the bow spring, and a bimetallic element operatively connected with the toggle member and serving upon changes in temperature above or below a predetermined critical temperature to pivotally move the said member so that the line of engagement between the said member and the end of the bow spring is shifted between positions at opposite sides of the strip and so that the bow spring is thus enabled to flex the resilient member and move the movable contact with a snap action into or out of engagement with the stationary contact in accordance with movements of the toggle member by the bimetallic element.

2. A thermostatic snap switch as set forth in claim 1 wherein the bow spring is formed as an integral part of the resilient metallic strip.

3. In a thermostatic switch, the combination of a resilient metallic strip rigidly supported at one end, a movable contact on the strip near the opposite end thereof, a stationary contact positioned to be engaged by the movable contact, a bimetallic element rigidly supported at one end, means connected with the bimetallic element adjacent the opposite end thereof for flexing the resilient strip to move the movable contact into or out of engagement with the stationary contact as the bimetallic element is deflected within normal predetermined limits in accordance with temperature changes within a narrow range, and stationary means for positively preventing deflection of the bimetallic strip beyond wider predetermined limits outside of the said normal predetermined limits when the said strip is subjected to temperatures outside of the said normal range.

4. In a thermostatic switch, the combination of a resilient metallic strip fixedly supported at one end, a movable contact on the strip near the opposite end thereof, a stationary contact positioned to be engaged by the movable contact, a bow spring connected at one end with the strip and having a free portion extending longitudinally toward the fixed end thereof, a toggle member mounted for pivotal movement about a transverse axis parallel with and adjacent the strip, the said member having pivotal engagement with the free end of the spring so that the spring is bowed and so that a toggle action is provided by the said member and the said spring, a bimetallic element connected with the toggle member and serving upon changes in temperature above or below a predetermined critical temperature to pivotally move the said member within normal predetermined limits so that the line of engagement between the member and the bow spring is shifted between positions at opposite sides of the strip and so that the bow spring is thus enabled to flex the strip and move the movable contact with a snap action into or out of engagement with the stationary contact in accordance with movements of the toggle member by the bimetallic element, and stationary means positioned to be engaged by the toggle member upon movement thereof beyond the said normal predetermined limits, the last said means positively preventing movements of the toggle member beyond wider

predetermined limits outside of the said normal predetermined limits.

5. In a thermostatic switch, the combination of a resilient metallic strip fixedly supported at one end, a movable contact on the strip near the opposite end thereof, a stationary contact positioned to be engaged by the movable contact, a bow spring connected at one end with the strip and having a free portion extending longitudinally toward the fixed end thereof, a toggle member mounted for pivotal movement about a transverse axis parallel with and adjacent the strip, the said member having pivotal engagement with the free end of the spring so that the spring is bowed and so that a toggle action is provided by the said member and the said spring and the said member having a transverse hole therein, a bimetallic element connected with the toggle member and serving upon changes in temperature above or below a predetermined critical temperature to pivotally move the said member within normal predetermined limits so that the line of engagement between the member and the bow spring is shifted between positions at opposite sides of the strip and so that the bow spring is thus enabled to flex the strip and move the movable contact with a snap action into or out of engagement with the stationary contact in accordance with movements of the toggle member by the bimetallic element, and a stationary pin extending into the hole in the toggle member and serving to positively prevent movements of the toggle member beyond wider predetermined limits outside of the said normal predetermined limits.

6. In a thermostatic switch, the combination of an insulating base, a bimetallic strip perpendicular to the base and circularly curved to substantially conform to the major portion of a geometric cylinder, means engaging the strip at one end to rigidly support it at the said end so that the remaining portion of the said strip is free and is adapted to deflect in accordance with temperature changes, a resilient metallic strip perpendicular to the base and located entirely within the said cylinder to which the bimetallic strip substantially conforms, the said strip being fixedly connected at one end with the base, a movable contact on the resilient strip near the opposite end thereof, a stationary contact on the base and positioned within the said cylinder for engagement by the said movable contact, and means within the said cylinder and connected with the free portion of the bimetallic strip for flexing the resilient strip to move the movable contact into or out of engagement with the stationary contact as the bimetallic strip is deflected in accordance with temperature changes.

7. A thermostatic switch as set forth in claim 6 wherein there is a means within the said cylinder for positively preventing deflection of the bimetallic strip beyond predetermined limits.

8. In a thermostatic switch, the combination of a circular insulating base, a bimetallic strip perpendicular to the base and circularly curved to substantially conform to the major portion of a geometric cylinder having a diameter slightly less than that of the base so that the strip may be closely adjacent a cylindrical casing surrounding and fitting the base, means engaging the strip at one end to rigidly support it at the said end so that the remaining portion of the said strip is free and is adapted to deflect in accordance with temperature changes, a resilient metallic strip perpendicular to the base and lo-

cated entirely within the said cylinder to which the bimetallic strip substantially conforms, the said strip being fixedly connected at one end with the base, a movable contact on the resilient strip near the opposite end thereof, a stationary contact on the base positioned within the said cylinder for engagement by the movable contact, and means within the said cylinder and connected with the free portion of the bimetallic strip for flexing the resilient strip to move the movable contact into or out of engagement with the stationary contact as the bimetallic strip is deflected in accordance with temperature changes.

9. In a thermostatic switch, the combination of an insulating base, a bimetallic strip perpendicular to the base and circularly curved to substantially conform to the major portion of a geometric cylinder, means engaging the strip at one end to rigidly support it at the said end so that the remaining portion of the said strip is free and is adapted to deflect in accordance with temperature changes, the said strip supporting means being connected with the base for pivotal movement about the axis of the said cylinder to which the bimetallic strip substantially conforms, a resilient metallic strip perpendicular to the base and located entirely within the said cylinder, the said strip being fixedly connected at one end with the base, a movable contact on the resilient strip near the opposite end thereof, a stationary contact on the base positioned within the said cylinder for engagement by the movable contact, means within the said cylinder and connected with the free portion of the bimetallic strip for flexing the resilient strip to move the movable contact into or out of engagement with the stationary contact as the bimetallic strip is deflected in accordance with temperature changes above or below a predetermined critical temperature, and means connected with the base within the said cylinder for adjusting the bimetallic strip supporting means about its pivotal axis so as to change the aforesaid critical temperature.

10. In a thermostatic switch, the combination of an insulating base, a bimetallic strip perpendicular to the base and circularly curved to substantially conform to the major portion of a geometric cylinder, means engaging the strip at one end to rigidly support it at the said end so that the remaining portion of the said strip is free and is adapted to deflect in accordance with temperature changes, a resilient metallic strip perpendicular to the base and located entirely within the cylinder to which the bimetallic strip substantially conforms, the said strip being fixedly connected at one end with the base, a movable contact on the resilient strip near the opposite end thereof, a stationary contact on the base positioned within the said cylinder for engagement by the movable contact, a bow spring connected at one end with the resilient strip near the contact carrying end thereof and extending longitudinally toward the fixed end of the said strip, a toggle member within the said cylinder mounted for pivotal movement about an axis perpendicular to the base and adjacent the fixed end of the resilient strip, the said member having pivotal engagement with the adjacent end of the bow spring so that the spring is bowed and so that a toggle action is provided by the said member and the said spring, and means connecting the free portion of the bimetallic strip with the toggle member to move the toggle member as the bimetallic strip is deflected in accordance with

temperature changes above and below a predetermined critical temperature, the said toggle member upon being so moved causing the axis of connection between the toggle member and the bow spring to shift between positions at opposite sides of the resilient strip with the result that the movable contact is moved with a snap action into or out of engagement with the stationary contact.

11. A thermostatic switch as set forth in claim 10, wherein the connecting means between the bimetallic strip and the toggle member is a pin carried by the toggle member and projecting through a hole in the bimetallic strip.
